UNITED STATES PATENT OFFICE.

LELAND A. PHILLIPS, OF ROCHESTER, NEW YORK.

BINDER FOR CARBON PAPER.

Application filed November 28, 1926. Serial No. 150,237.

The object of this invention is to provide a new and improved binder for carbon paper, one that can be readily fed behind the platen of a typewriter or other writing and copying machine.

Another object of this invention is to construct this binder so that different grades or colors of carbon paper sheets may be automatically brought together each in a predetermined place with relation to the others and then bound into the binder.

Another object of this invention is to provide an uncoated strip on each of the carbon sheets overhanging the binder to allow the carbon sheets to be readily picked up previous to the insertion of the copy paper without soiling the fingers in doing so.

Another object of this invention is to provide means in both the carbon sheets and the binder to allow a quick withdrawal of the original as well as copy sheets from the binder.

These and other objects of the invention will be fully illustrated in the drawing, described in the specification and pointed out in the claims at the end thereof.

In the accompanying drawing:

Figure 1 is a perspective view of the improved carbon paper binder with the original and copy sheets inserted therein.

Figure 2 is a longitudinal sectional view of the binder illustrated in Figure 1.

Figure 3 is an enlarged sectional view of a corner of the binder made up with more than one carbon sheet.

Figure 4 is a diagrammatic view of the method of making the carbon binder.

In the several figures of the drawing like reference numerals indicate like parts.

In manifolding copies on a typewriter or other writing and copying machine such as bookkeeping machines, it is the common practice at the present time to alternately place the loose paper sheets and carbon sheets together and then line them up with relation to each other. As the carbon sheets are usually very thin it is difficult to get these sheets in proper alignment with each other. It is especially troublesome to get

the paper sheets in place when the carbon sheets have been used before and have lost some of their stiffness. The more the loose sheets of carbon paper are handled the more they are mussed up, lose their coating and soil the fingers so that much of the coating is lost due to the manual handling of each of

the carbon sheets, besides what is lost in writing. While carbon sheet binders have heretofore been made and sold, their construction has been such as to make their use 60 impractical and their cost of manufacture so high as to practically prohibit their use in competition with the loose carbon sheets.

The binder and its construction forming the subject matter of this invention eliminates the drawbacks of earlier attempts to market such a binder in that applicant's construction in making it insures a low cost due to the fact that quantity production is possible at low cost and the manner in which 70 the binder is made permits also the ready insertion and use of it in the typewriter or other machine.

It will be readily understood that carbon paper sheets when bound into a binder will be serviceable much longer than loose carbon sheets because the back of the binder keeps the sheets flat and protects the coated side against contact with everything except the copy paper that is placed underneath it. 75 As illustrated in the figures of the drawing each binder consists of the backing sheet 1, the carbon sheet or sheets 2 and the binding strip 3. A small strip 4 at the bottom of the carbon sheet and overhanging the bottom of the backing sheet is not coated so that the carbon sheet can be lifted by means of this strip without placing the fingers in contact with the carbon coating of the carbon paper. The upper edge of the carbon sheet extending underneath the binding strip 3 is preferably also left uncoated which serves to reduce the thickness of the upper edge of the complete carbon binder especially one containing more than one sheet of carbon paper. 85

Both the carbon sheet or sheets and the backing sheet are notched preferably at the lower right hand corner as illustrated at 5 and 6 respectively so that the sheets of record paper placed into the binder can be gripped by the fingers in this notch without gripping either the carbon sheet or the backing sheet. In this way the top record sheet as well as the manifold copies thereof can be gripped and simultaneously pulled out 90 of the binder without having to individually separate the paper sheets from carbon sheets.

The binding strip 3 is sewed to the carbon sheet or sheets 2 and to the backing sheet 1 and is located on top of the binder 110 so that a portion of its outer edge overhangs both the carbon sheets and the back-

ing sheet. When therefore all of the sheets making up the binder are fastened together there is a thin edge of a single thickness provided at the top of the binder, which 5 when fed behind the roller plate of the typewriter will extend far enough behind the platen so that on the rotation of the roller platen the binder is easily gripped by it and fed into position. The top edge of the 10 binder is thus made wedge shaped which is necessary in order to have the binder feed behind the roller platen.

The seam 7 formed by stitching the binding strip to the carbon sheets and backing 15 sheet serves as a stop against which the top paper sheet as well as the manifold copy sheets are placed when inserting these sheets into the binder. The seam is straight and parallel with both the top and bottom of 20 the binder so that the paper sheets inserted into the binder and resting against the seam are properly located with relation to each other and to the binder without having to line them up after they have been placed 25 into the binder.

The fact that the binding strip is fastened as a separate strip to the binder makes it 30 possible to employ a method that will make the binder automatically at such a rapid rate of speed that quantity production of 35 the binder is possible at low cost. This quantity production reduces the cost of making the binder to such a low figure that in view of the many advantages secured by 40 the binder it can compete with carbon sheets furnished unbound without the binder.

While I have shown and described the 45 binder as being assembled by means of thread, the fact that a strip at the upper edge of the carbon paper is left uncoated makes it possible to apply an adhesive to the carbon paper and the backing sheet and binding strip and assemble the binder by means of an adhesive instead of a thread.

I claim:

1. A carbon binder comprising a backing sheet, a carbon sheet, a binding strip, means for fastening said sheets together with said binding strip overlapping said backing sheet 50 at one end and said carbon sheet overlapping said backing sheet at the other end.

2. A carbon binder comprising a backing

sheet, a carbon sheet and a binding strip fastened together at one end, an uncoated strip provided on said carbon sheet and 55 overhanging said backing sheet at the bottom, said binding strip overhanging the bound edge of said carbon sheet to form a thin wedge in front thereof.

3. A carbon binder comprising a backing 60 sheet, a carbon sheet and a binding strip, an uncoated strip provided at one end of said carbon sheet overhanging said backing sheet, an uncoated strip provided at the other end of said carbon sheet and located 65 above said backing sheet and means for fastening said binding strip to said backing sheet with said uncoated strip located between them and with a portion of said binding strip overhanging the bound edge of 70 said uncoated strip to form a thin wedge in front thereof, the overhanging portion of said binding strip and the uncoated portion of the carbon sheet serving to reduce the thickness and form a wedge on the top of 75 the binder that is adapted to be easily passed under the roller platen of a typewriter.

4. A carbon binder comprising a backing sheet, a carbon sheet, a binding strip, means for fastening said sheets together with said 80 binding strip overlapping said backing sheet at the bound end and said carbon sheet overlapping said backing sheet at the free end, each of said carbon sheets being notched at 85 the bottom of the sheets to allow the paper sheets inserted into the binder between the carbon sheets to be gripped and withdrawn 90 from the binder at one operation.

5. A carbon binder comprising a backing sheet, a carbon sheet on top of said backing 95 sheet, a binding strip made up of a single thickness of thin paper stock located on top of said carbon paper and stitched to said carbon paper and said backing sheet to fasten the binding strip, carbon sheet and backing sheet together on top of one another at one end thereof, said binding strip projecting beyond the stitched ends of said carbon sheet and backing sheet to cover the end of the carbon sheet and backing sheet and 100 form a thin starting wedge for said binder.

In testimony whereof I affix my signature.

LELAND A. PHILLIPS.
